UNITED STATES PATENT OFFICE.

LAURENCE P. SHANNON, OF WASHINGTON, DISTRICT OF COLUMBIA.

CASE FOR CIGARETTES, &c.

1,071,629.

Specification of Letters Patent. Patented Aug. 26, 1913.

Application filed May 5, 1913. Serial No. 765,521.

To all whom it may concern:

Be it known that I, LAURENCE P. SHANNON, a citizen of the United States, residing at Washington city, District of Columbia, have invented certain new and useful Improvements in Cases for Cigarettes, &c., of which the following is a specification.

This invention, in a general way, relates to that class of containers or packages adapted to dispense or discharge articles contained therein one by one, and broadly considered, may be constructed of various materials, as for instance indurated fiber, molded paper pulp or the various metals, depending on the articles to be contained and dispensed, and on the taste, and finances of the purchaser or user. For instance, these packages may be used to contain and dispense cigars, stogies, cigarettes, etc., and if constructed of inexpensive material may be used as mediums of advertisement, or they may be constructed of expensive metals to be carried and used continuously by persons of extravagant tastes.

With this understanding of its general scope, I have chosen to illustrate and describe my invention as embodied in a cigarette case.

One object of my invention is to prevent the handling of cigarettes of a package, before use by an individual, and to this end I provide for the discharge of a single cigarette as it is required for use, and that to the individual intending to use it.

A further object is to provide an article of this character extremely simple and inexpensive in construction, and readily manipulated, either to fill or to discharge cigarettes.

A further object of the invention is to provide a receptacle of this character with a means embodying the functions of a latch to prevent or permit the separation of the cover and holder, and also the functions of an ejector.

With these objects in view my invention consists in details of construction, and combinations, to be particularly described hereinafter, and briefly set forth in the claims.

In the accompanying drawings, Figure 1 is a side elevation of a cigarette case embodying my improvements, the parts being shown in position wherein the first of a row of cigarettes will have been moved upward with relation to said row. Fig. 2 is a vertical section of the case, in closed position

with the first of a row of cigarettes resting on the ejecting detent. Fig. 3 is an end elevation of the case, the dotted lines indicating the combined latch and ejector in position to permit the separation of the holder and cover for filling the former. Fig. 4 is a vertical section taken on line 4—4 of Fig. 2 looking in the direction of the arrows. Fig. 5 is a top plan view of the case.

The same reference characters are used in the several figures of the drawing to designate like parts.

My cigarette case comprises an outer shell or cover A closed on all sides but one, and a receptacle or holder B for cigarettes adapted to slide freely within the cover.

The cover A consists of side walls 1 and 2, end walls 3 and 4, and a top wall 5, cut away adjacent the end wall 4 leaving an opening 6 to admit of the passage of a cigarette therethrough.

The holder B consists of side walls 7 and 8, end walls 9 and 10, and a bottom wall 11, and those so far constructed have been of a size to hold ten ordinary cigarettes and a leaf spring, and are so proportioned with relation to the cover A, as to slide freely therein but without lost motion.

To save metal and weight the front wall 7 of the holder terminates at about a third the height of the rear wall 8, and the latter is provided at top with a narrow flange 8^a terminating short of the end wall 10 to leave the opening 6 in the top wall of the cover unobstructed. I do not deem this flange essential, but prefer its employment as it prevents other than the end cigarette from riding up due to possible contact of one side of the cigarettes with the front wall 7 of the cover, at a point above the shortened front wall 7 of the holder.

Pivoted or secured to the end wall 4 of the cover A, is a latch 12 terminating at its free end in a right-angled tongue 13, which, when the holder B is closed within the cover A may be moved through a slot 14 formed in the lower corner of the wall 7 of the holder B and through a notch 15 in the lower corner of the wall 1 of the cover A (see Fig. 4) thus permitting the cover to be removed from the holder in order that the latter may be filled with cigarettes.

In order that the latch 12 may, normally, be retained in the position shown in Fig. 3, I provide the wall 4 and latch with engaging parts, those shown consisting of a boss

16 projecting from the wall 4, and a recess
17 formed in the latch, as best shown in Fig.
2. These may be conveniently formed by
pressing the metal of these parts in a man-
5 ner well understood.

The cases thus far constructed, in carrying out my invention have been of metal, and the latch 12 has been resilient in order that it might be sprung outward from the 10 end wall 4 of the cover to which it is secured, sufficiently to free the tongue 13 from the slot 19 in the end wall 10 of the holder, as indicated by broken lines in Fig. 2, thereby admitting of the withdrawal of the 15 holder from the open end of the cover for the purpose of refilling said holder, and when these parts are again telescoped together the latch may be released and the tongue 13 will enter the slot 19 and thus 20 again lock the two parts of the case together and prevent separation thereof, except by further manipulation of the latch 12.

As so far described the operation of my device is as follows:—Assuming that the 25 holder B is filled or partly filled with cigarettes, (as in Fig. 2) it will be noted that the cigarette adjacent the end wall 10 and 4 of the holder and cover rests upon the tongue or detent 13 of the latch 12, the row 30 of cigarettes being gently pressed toward that end by the light spring 18 of any approved form, which is inserted in the holder between the cigarettes and the end wall 9 of the holder. Upon moving the 35 holder and cover with relation to each other, into the position shown in Fig. 1, the detent 13 will move upward in slot 19 of wall 10, and it follows that the end cigarette will be moved upward within the holder, away from 40 the row (as indicated by dotted lines in Fig. 1) the tip end thereof being just beneath the opening 6 of the cover top 5. Upon now again moving the parts together the end of said end cigarette of the row will be projected sufficiently beyond the top of the 45 cover to be grasped by the lips or the fingers, for though the detent 13 will have ceased to support it, the friction between adjacent cigarettes, and the end cigarette and the end 50 wall 10 of the holder will be sufficient to retain it in place, but to insure against possible failure to operate as described I prefer to form a slight transverse ridge 20 in the wall 10 of the holder that will tend to indent the cigarette slightly thus holding it 55 securely against being carried downward by frictional contact with the next adjacent cigarette.

As a further and distinct improvement, I 60 prefer the slide 21 to cover or expose the opening 6 in the top wall 5 of the cover, to prevent escape of tobacco from the case into the pocket of a user, and this also tends

to keep the cigarettes from becoming dry from exposure to air. In carrying out this 65 feature of the invention the side walls 1 and 2 of the cover are pressed to form outwardly projecting longitudinal bosses 22 and 23 at the inner end of which are formed stops 24. The slide 21 has a flat top and 70 parallel side wings, these wings having parallel grooves to ride upon the longitudinal bosses 22 and 23, as shown in Figs. 1, 4, and 5. The flat top of the slide is shown as provided with a boss for engagement by 75 the thumb or finger, and also as being roughened for a like purpose.

It will be understood that such a case is operable without the presence of the spring 18, as the case may be turned with its wall 80 4 and 10 downward, and the cigarette would move by gravity toward said walls, thus lodging the endmost cigarette of a row upon the detent 13, further manipulation being 85 apparent.

Claims.

1. A cigarette case consisting of a cover having two side walls, two end walls, a top wall having a slot adjacent one end wall, and an open bottom; a holder having two 90 side walls, two end walls, a bottom wall and an open top, one of said end walls being slotted adjacent the bottom wall; and a resilient L-shaped member secured to an end wall of the cover and adapted to protrude 95 through the slot in the end wall of the holder and fulfil the dual functions of a latch to prevent separation of the holder and cover, and of an ejector, or to be withdrawn from the slot in the holder to permit the removal thereof from the cover.

2. A cigarette case consisting of a cover and a holder fitting therein, said cover having an open bottom and an opening in the top wall adjacent to one end wall, said end 105 wall having a combined latch and ejector pivoted exteriorly thereto, and said holder being open at top and having one end wall slotted at the lower end to receive the tongue or detent of the latch and ejector, 110 one side wall of the holder being provided at top with a flange terminating opposite the inner end of the slot in the top wall of the cover, a spring being seated in said holder between its bottom wall and the 115 flange of the side wall, the lower corners of the holder and cover being slotted and notched respectively to admit the passage of the tongue of the combined latch and ejector.

In testimony whereof I affix my signature in presence of two witnesses.

LAURENCE P. SHANNON.
